QUILL CHECK FOR NARROW WARE LOOM

Allan S. Hutchins, Oakham, Mass., assignor to Crompton & Knowles Loom Works, Worcester, Mass., a corporation of Massachusetts

Application December 14, 1953, Serial No. 397,907

10 Claims. (Cl. 139—136)

This invention relates to improvements in looms more particularly of the narrow ware type and it is the general object of the invention to provide means for preventing overrun of the quill when the shuttle reaches the end of its travel.

Shuttles for narrow ware looms ordinarily employ a quill which rotates on a pin or the like to pay off weft for the weaving operation. It is customary to use a pad tension which presses against the weft of a quill to serve the purpose of creating tension in the weft and also act to some extent as a brake on the quill. When large quills are used, however, especially when they are fully wound, their momentum of rotation is such that the pad tension is not sufficient to stop their rotation when the shuttle comes to rest with the result that excess weft is paid off and is likely to produce a slack pick.

It is the general object of the present invention to provide a shuttle operated brake or check which shall be moved against the quill to arrest its turning as the shuttle approaches the end of its travel.

The lays of narrow ware looms are ordinarily provided with spaced shuttle blocks which receive the shuttles as they are moved in a direction generally lengthwise of the lay. It is a further object of the invention to mount on each shuttle block a quill check which is normally out of the path of the shuttle but is operated by an actuator means normally in the path of the shuttle and moved by the latter to press the checking means against the quill when the shuttle is near the end of its travel in the block.

It is a still further object of the invention to make the checking and actuating means in the form of arms which are pivoted together and held in normal position by a spring which can yield to permit continued motion of the actuating arm by the shuttle after the checking arm has engaged the quill.

It is a still further object of the invention to pivot the checking and actuating arms to each other and provide resilient means such as a spring which holds the two arms in their normal positions but can yield to permit movement by the shuttle. Stop means are provided to cooperate with the spring to hold the actuating arm in correct position for engagement by the shuttle.

A still further object is to provide a checking unit which can be readily mounted on a pivot on the shuttle block.

In order that the invention may be clearly understood reference is made to the accompanying drawings which illustrate by way of example the embodiments of the invention and in which:

Fig. 1 is a front elevation of part of a narrow ware loom showing two shuttle blocks each equipped with a pair of shuttle check units made according to the invention.

Fig. 2 is an enlarged plan view looking in the direction of arrow 2, Fig. 1.

Fig. 3 is an enlarged detailed front elevation looking

2

in the direction of arrow 3, Fig. 2, showing a shuttle approaching the end of its travel in a shuttle block but with the checking member spaced from the welt quill in the shuttle.

Fig. 4 is a view similar to Fig. 3 but shows the shuttle at the end of its path of movement with the check in contact with the quill.

Fig. 5 is an enlarged section on line 5—5, Fig. 4.

Fig. 6 is an enlarged detailed section on line 6—6, Fig. 4, and

Fig. 7 is an enlarged fragmentary section on line 7—7, Fig. 3.

Referring particularly to Fig. 1, the breast beam of the loom is indicated at 1 and the lay at 2. The lay has secured thereto a plurality of shuttle blocks extending upwardly therefrom, two of these blocks being shown herein at 3 and 4. Beat-up reeds 5 are between the blocks and the latter are provided with intersecting arcuate grooves so that they can accommodate two shuttles, one at a time. Thus, each block has intersecting grooves 6 and 7, groove 7 in block 3 being a continuation of groove 6 in block 4. Two shuttles S1 and S2 are shown in Fig. 1, shuttle S1 being in groove 7 of block 3 and shuttle S2 being in a groove 7 of block 4.

These shuttles are alike, the shuttle S1 as shown in Fig. 2 having a quill space 10 and a pin 11 on which is mounted for rotation a quill 12 wound with a mass of weft W which unwinds during the weaving operation and passes successively through eyes 13, 14, 15 and 16. The eyes 14 and 15 are mounted on springs 17 so that they can be retracted to take up slack in weft. The eye 13 is on the inside of the bridge 18 of the shuttle and the eye 16 is the delivery eye through which the welt passes as it leaves the shuttle. The shuttles are operated in the usual manner as by pinions 20 and a rack rod 21. The usual shuttle carried tension pad is shown at 22 in Fig. 2.

During operation of the loom the lay swings backwardly and forwardly in usual manner and the rack rod is reciprocated along it to cause each shuttle to move from one block across a reed space to an adjacent block. Thus, on one beat of the loom shuttle S1 will be in groove 7 of block 3 as shown in Fig. 1, and on the next beat shuttle S1 will be in groove 6 of shuttle block 4. The weft thread unwinds from the quills and when the latter are fully wound and of large size they have a tendency to continue to rotate after the shuttle comes to rest, thereby unwinding more weft than can be accommodated by the eyes 14 and 15. The result of this continued rotation is to make the weft slack so that it is not drawn tightly in the fabric.

In carrying the invention into effect each shuttle block is provided with checking means to cooperate with each of the two shuttles which it can accommodate. As shown in Fig. 1 two checking units U1 and U2 are mounted on shuttle block 3 and two other checking units U3 and U4 are mounted on shuttle block 4. The checking units U1 and U3 are the same while the units U2 and U4 are similar but of the opposite hand. A detailed description will be given of but one of these units, namely unit U1, and it will be understood that the description of this unit will suffice for the other units.

Referring particularly to Figs. 3 and 4, shuttle block 3 is provided with a fixed pivot 25 extending forwardly therefrom and is also provided with a pin 26 to which is attached one end of a positioning spring 27. The unit U1 includes in its construction an actuating means or arm 30 having a bearing 31 to fit the pivot 25. A cotter pin or the like 32 holds the arm 30 in position on the pivot. The left end of the arm 30 is provided with a stud 33 having a head 34 and a roll 35 located

between the head 34 and the arm 30, see Fig. 6. This roll is adapted for engagement with the left end 36 of shuttle S1. The arm 30 is also provided with an attaching means 37 for the left end of spring 27, and the block 3 has a stop pin 38 which limits counterclockwise movement of the arm 30 around pivot 25. The spring 27 cooperates with the pivot 25 and the stop 38 to maintain the roll 35 in the path of the shuttle, but in such position that the roll can be raised by the shuttle. The actuating arm 30 also has a stop 39 projecting forwardly therefrom for a purpose to be set forth.

The unit U1 includes a checking arm 40 having on the outer end thereof a roll 41 which may be similar to roll 35 for engagement with the quill 12 of the shuttle. A pivotal connection between the arms 30 and 40 includes a stud 42 screw threaded at 43 into arm 30 and having a lock nut 44 to hold the stud 42 firmly in position on the arm 30. The upper end of the arm 40 is pivoted on the shank 45 of stud 42 and the latter has a head 46 to limit forward movement of the arm 40. Formed integral with and extending upwardly from the arm 40 is a stop element or finger 47 for engagement with the previously described stop 39 on the arm 30.

A spring 50 has a coiled part 51 thereof surrounding the stud 42 and has two arms extending from the coiled part, one of these arms 52 extending to the left and being bent to fit into a notch 53 in the top of arm 30, and the other arm 55 extending along arm 40 and bent to fit into a notch 56 in arm 40. A spring 50 has the effect of holding the stop elements 39 and 47 against each other but permitting the arms 30 and 40 to move angularly with respect to each other around the pivotal connection.

As shuttle S1 moves to the left, but before reaching the end of its path of travel, unit U1 will be in the position shown in Fig. 3, spring 27 and the stop 38 cooperating to hold the unit with roll 35 positioned for engagement with the advancing left end of the shuttle and with roll 41 spaced above the path of the shuttle and out of engaging position relative to the quill 12. As the shuttle S1 continues to move to the position shown in Fig. 4 it will lift the roll 35 and rock the unit in a clockwise direction around pivot 25, thereby lowering the roll 41 against the quill the effect of which is to arrest rotation of the quill. The diameter of the weft on the quill will diminish as weft is drawn from it so that the amount of motion of the roll 41 necessary to engage the quill will vary from a full quill to a nearly empty one. When the quill is full there will be a comparatively large relative angular motion of the arms 30 and 40 around their pivotal connection after roll 41 engages the quill, this angular motion being permitted by the spring 50 as the stops 39 and 47 separate from each other. When the quill is almost empty the relative angular motion of the arms or members 30 and 40 will be less. For all diameters of the yarn on the quill however the actuator arm 30 will provide sufficient motion to move the roll 41 against the weft of the quill.

It is to be understood that the unit U3 will operate as does unit U1 when shuttle S2 moves to the left hand end of its path of motion, and that unit U4 will act to check rotation of the quill of shuttle S1 when the latter is in block 4, the angular motion of the parts of the unit U4 being opposite to that already described in connection with the operation of unit U1. The unit U2 will act on another shuttle not shown herein, coming from the left as viewed in Fig. 1, and entering block 3 as shuttles S1 and S2 are moved to the right from the positions shown in Fig. 1.

From the foregoing it will be seen that the invention sets forth a checking means for the quills of narrow ware shuttles operated by the latter as they near the end of their path of movement in the shuttle blocks. Each unit includes two arms or members 30 and 40 which are pivoted to each other and are movable jointly around the

pivot 25. The spring 27 holds the actuating arm roll 35 in position for engagement with the shuttle, thus enabling the latter when approaching the end of its travel to rock the unit around the pivot 25 and cause roll 41 of the checking arm to engage the quill. The spring 50 permits a varying degree of relative angular motion of the arms 30 and 40 depending upon the diameter of the quill. Also, spring 27 cooperates with the pivot 25 and the stop 38 to perform two functions one of which is to locate the roll 35 normally in the path of the shuttle, and the other of which is to hold the roll 41 out of the path of the shuttle and quill prior to arrival of the shuttle at the point near the end of its path of movement. Furthermore, the invention provides a novel check unit which can be readily applied to pivot 25.

Having now particularly described and ascertained the nature of the invention and in what manner the same is to be performed, what is claimed is:

1. In a narrow ware loom having a lay and a shuttle moving with respect to the lay along a path during loom operation and provided with a weft quill rotatable thereon, quill checking means independent of the shuttle normally spaced from the quill mounted on the lay for movement against the quill, and means pivoted on the lay operated by the shuttle as the latter approaches the second named means near the end of said path to cause said checking means to move against said quill to resist rotation thereof.

2. In a narrow ware loom having a shuttle movable along a path and provided with a rotatable weft quill which has a tendency to continue to rotate as the shuttle approaches the end of said path, quill checking means normally spaced from the quill mounted for movement against the quill, and an actuating arm normally extending into said path to be engaged and moved by the shuttle to cause said checking means to move against the quill to arrest said tendency thereof to rotate.

3. In a quill checking unit for application to a narrow ware loom shuttle block having a pivot and a positioning spring thereon, an actuating member having a shuttle engaging element on one end thereof and having a bearing therein to receive said pivot, a quill checking member having a quill engaging element at one end thereof, a pivotal connection between the other ends of said members, a stop on one of said members, a stop element on the other member to engage said stop, resilient means normally holding said stop element against said stop yieldable to permit relative angular motion of said members around said pivotal connection, and attaching means on one of said members for said positioning spring enabling said spring and pivot to cooperate to hold the unit in normal position when the unit is supported by said pivot but permitting said unit to move angularly around said pivot.

4. The checking unit set forth in claim 3 wherein the resilient means is a spring having part thereof coiled around said pivotal connections and having two arms extending from the coiled part thereof, one arm for the actuating member and the other for the checking member.

5. In a narrow ware loom having a shuttle movable along a path and provided with a rotatable weft quill which has a tendency to continue to rotate as the shuttle approaches the end of said path, quill checking means including a roll rotatably mounted thereon for engagement with the quill and being normally spaced from the quill and mounted for movement against the quill, and actuating means operated by the shuttle as the latter approaches the end of said path to cause said checking means to move against the quill to resist said tendency thereof to rotate.

6. In a narrow ware loom having a shuttle movable along a path and provided with a rotatable weft quill which has a tendency to continue to rotate as the shuttle approaches the end of said path, quill checking means normally spaced from the quill mounted for movement against the quill, actuating means operated by the shuttle

as the latter approaches the end of said path, a stop member limiting movement of said actuating means toward said path, and a spring connected to one of said means to hold one of said means against said stop member to place the actuating means normally in said path.

7. In a narrow ware loom having a shuttle moving along a path during loom operation and provided with a weft quill rotatable thereon, quill checking means normally spaced from the quill mounted for movement against the quill, actuating means operated by the shuttle as the latter approaches the end of said path, said checking and actuating means being pivoted to each other and having mutually engaging stop elements, and a spring holding said angular movement of said checking and actuating means in a direction to separate said stop elements.

8. In a narrow ware loom having a shuttle moving along a path during loom operation and provided with a weft quill rotatable thereon, quill checking means normally spaced from the quill mounted for movement against the quill, actuating means operated by the shut-

15

20

tle as the latter approaches the end of said path, said actuating means being an arm swingable on a pivot on the lay for movement in a direction away from said path due to engagement with the shuttle and when having said movement causing said checking means to move against the quill.

9. The structure set forth in claim 8 wherein said checking means is pivoted to said actuating arm, and resilient positioning means normally holds the checking arm spaced from the quill and also holds the actuating arm in said path.

10. The structure set forth in claim 9 wherein a stop cooperates with said positioning means to limit movement of the actuating means toward said path.
